(57) **ABSTRACT**

A cap protector includes a unitary rigid shell having an open rear in communication with an interior chamber that is dimensioned and configured to receive the crown portion of a cap. Integrally extending from the lower, front portion of the shell is a substantially planar panel configured to resemble the cap's bill. The panel includes a slot in communication with an interior cavity that is dimensioned to firmly receive the cap bill. On the upper surface of the shell is a grommet with a locking mechanism that grips the cap's crown button.

CAP PROTECTOR

CROSS REFERENCE TO RELATED APPLICATIONS

This application claims priority of provisional application No. 63/054,350 filed on Jul. 21, 2020, the specification of which is incorporated herein by reference.

BACKGROUND OF THE INVENTION

The present invention relates to a unitary shell for protecting a ball cap during transport or storage.

DESCRIPTION OF THE PRIOR ART

Storing or transporting a ball cap has always been challenging and problematic. If placed on a shelf, the cap collects mold and dust. If the shelf is exposed to sunlight, the cap's fabric or logo can fade significantly and diminish the cap's value, particularly if it is a collector's item. If multiple caps are stacked, the lowermost caps get crushed and deformed. Suspending the cap by the rear adjustment strap causes the cap to elongate and fit poorly when ready to wear.

Transporting a cap within a suitcase or other luggage item is particularly challenging. The crown is often compressed by clothing, causing the fabric and logo to wrinkle and the bill to bend. If the bill is bent to a certain angle, the cap may be ruined. Cap wearers who are fastidious about cap appearance are severely annoyed if forced to wear a deformed cap.

Accordingly, there is currently a need for a device that protects a cap from debris, sunlight and deformation while being stored. The present invention satisfies this need by providing a unitary, rigid shell having a pair of cavities for receiving the bill and crown of a cap to prevent deformation.

SUMMARY OF THE INVENTION

The present invention relates to a cap protector comprising a unitary rigid shell having an open rear in communication with an interior chamber that is dimensioned and configured to receive the crown portion of a particular cap. Integrally extending from the lower, front portion of the shell is a substantially planar panel configured to resemble the cap's bill. The panel includes a slot in communication with an interior cavity that is dimensioned to firmly receive the cap bill. On the upper surface of the shell is a grommet with a locking mechanism that grips the cap's crown button.

It is therefore an object of the present invention to provide a device that protects the structural integrity of a cap during transport and storage.

It is therefore another object of the present invention to provide a cap protector constructed with a lightweight, rigid material that prevents a cap bill from bending or the crown from collapsing.

It is yet another object of the present invention to provide a cap protector having a unique locking system for gripping a cap's crown button.

Other objects, features, and advantages of the present invention will become readily apparent from the following detailed description of the preferred embodiment when considered with the attached drawings and the appended claims.

BRIEF DESCRIPTION OF THE DRAWINGS

FIG. 1 depicts the protector according to the present invention being used to store a cap in a luggage item.

2

FIG. 2 is an isolated, rear perspective view of the cap protector.

FIG. 3 is an isolated, front perspective view of the cap protector.

5 FIG. 4 depicts a cap being inserted into the cap protector.

FIG. 5 depicts a cap being stored within the cap protector.

FIG. 6 is a top view of the cap protector.

FIG. 7 is a front view of the cap protector.

FIG. 8 is a sectional view of the button retainer.

DESCRIPTION OF THE PREFERRED EMBODIMENT

15 The present invention relates to a protector 100 for protecting the structural integrity of a given cap 102 when packed within a luggage item 104 or placed within another storage location. The cap 102 includes a bill 122, a crown 126, and peripheral portion 124 that are easily crushed or deformed when stored. The protector 100 according to the present invention comprises a unitary, rigid shell 110 having an upper surface 114, a front surface 66, a lower edge, an outer wall 70, and an open rear 80 in communication with an interior chamber 116 that is dimensioned and configured to receive the crown portion 126 of a particular cap, i.e., a baseball style cap. The front surface may include a logo, artwork, design elements or similar ornamentation. The shell 110 is preferably constructed with polypropylene plastic or a similar lightweight, rigid material that prevents an enclosed cap from being crushed when stored. Integrally extending from the lower edge of the front surface is a substantially planar panel 118 configured to resemble the bill of the cap. The panel 118 includes a slot in communication with an interior cavity 108 that is dimensioned to firmly receive the cap bill 122.

20 On the upper surface of the interior crown chamber 116 is a grommet 106 that is dimensioned to receive the cap's button 112. Within the grommet 106 is a button retainer including a pair of resilient, biased fingers 128 that separate slightly when subjected to force but return to an original position when released to firmly grip the lower surface of the button 112. The button includes a tactile membrane that emits a clicking noise to alert a user that the button has been 25 fully inserted.

30 As readily apparent from the detailed description, the present invention provides an easy and convenient means of storing and protecting a cap to prevent crushing, distorting, or bending. To store a cap, a user inserts the cap bill into the 35 protector cavity 108, folds the rear section of cap crown 126 against the front portion of the crown 126 and the interior surface of the cap's front surface 66. The button 112 is then pushed into the button retainer until the user hears a click, which indicates that the crown button is locked within the 40 grommet.

45 The above-described device is not limited to the exact details of construction and enumeration of parts provided herein. Furthermore, the size, shape and materials of construction of the various components can be varied without departing from the spirit of the present invention.

50 Although there has been shown and described the preferred embodiment of the present invention, it will be readily apparent to those skilled in the art that modifications may be 55 made thereto which do not exceed the scope of the appended 60 claims. Therefore, the scope of the invention is only to be 65 limited by the following claims.

What is claimed is:

1. A cap protector comprising:

a shell having an upper surface, a front surface and an open rear in communication with an interior chamber, said interior chamber dimensioned and configured to receive a crown portion of a cap;
 a panel extending from the front surface of said shell, said panel having a slot in communication with an interior cavity that is dimensioned to receive a bill of the cap; a grommet on the upper surface of said shell, said grommet dimensioned to receive a crown button on said cap.

2. The cap protector according to claim 1 wherein said shell is constructed with a rigid material that prevents the cap enclosed within the cap protector from being crushed when stored.

3. The cap protector according to claim 1 further comprising a button retainer within said grommet, said button retainer including a pair of resilient, biased fingers that separate when subjected to force but return to an original position when released to firmly grip a lower surface of the crown button.

4. A combination of a cap protector and a cap, the cap comprising a bill, a crown, a peripheral portion and a button on said crown; the cap protector comprising a shell having an upper surface, a front surface and an open rear in communication with an interior chamber, said interior chamber receiving said crown; and a panel extending from the front surface of said shell, said panel having a slot in communication with an interior cavity, said bill received within said cavity, and a grommet on the upper surface of said shell, said button received within said grommet.

5. The combination according to claim 4 wherein said shell is constructed with a rigid material that prevents the crown and said bill from bending or contorting.

6. The combination according to claim 4 further comprising a button retainer within said grommet, said button retainer including a pair of resilient, biased fingers that separate when subjected to force but return to an original position when released to firmly grip a lower surface of said button.
